UNITED STATES PATENT OFFICE.

CARLETON SPRAGUE, OF BUFFALO, NEW YORK.

BOILER.

SPECIFICATION forming part of Letters Patent No. 440,284, dated November 11, 1890.

Application filed May 2, 1890. Serial No. 350,280. (No model.)

To all whom it may concern:

Be it known that I, CARLETON SPRAGUE, of Buffalo, in the county of Erie, in the State of New York, have invented new and useful Improvements in Boilers, of which the following, taken in connection with the accompanying drawings, is a full, clear, and exact description.

My invention relates to an improved boiler, and has for its object the production of a simple and effective construction, which is more durable, effective, and desirable than those previously devised; and to this end it consists, essentially, in a boiler-shell having an upward extension, an annular bearing or ring provided upon the outside of said extension, a smoke-box removably secured to said bearing, whereby the said combustion-box may be readily removed when defective or worn out and replaced by a new one at a minimum cost and without necessitating the replacement of the entire boiler-shell extension.

The invention also consists in providing said ring or removable combustion-box with a bearing in front of the securing-point of the rear flue-sheet and in forming the said bearing of greater thickness than the securing-rivets for said flue-sheet, whereby the mounting and removing of said combustion-box are enabled without necessitating the slightest injury to said securing-rivets.

The invention still furthermore consists in the detail construction and arrangement of the parts, all as hereinafter more particularly described, and pointed out in the claims.

In describing this invention reference is had to the accompanying drawings, forming a part of this specification, in which like letters indicate corresponding parts in all the views.

Figure 1 represents a longitudinal vertical section illustrating the relative construction and arrangement of the parts of my improved construction of boiler. Fig. 2 is an end elevation of the boiler-extension with the cap or cover thereof removed for the purpose of illustration, and Fig. 3 is an enlarged sectional detail view illustrating the means for securing the flue-sheet and removable combustion-box to the boiler-shell extension.

A represents the boiler shell or casing formed of suitable size and material and provided with the forward extension A', which

is preferably of circular form. Secured to the boiler-shell and its extension are the front and rear flue-sheets B and C.

55

The fire-box D is of any suitable construction, size, or shape, and is provided with a desirable form of grate E. Opening from the fire-box D is the fire flue or passage F, secured at its rear extremity to the rear flue-sheet C 60 and preferably to a forwardly-turned flange c near the base of said flue-sheet.

Provided upon the extension A', and preferably in front of the securing-rivets c' of the rear flue-sheet, is a bearing G, which preferably consists of a wrought-iron ring operatively secured by rivets or other suitable means g. As best seen in Fig. 3, the said ring G is of greater thickness than the head c² of the securing means c', and supported upon said ring is the combustion-box H, of suitable size. This combustion-box is removably held in operative position by means of screws or other securing means g', which, as best shown in Fig. 2, are arranged at intervals around the 70 forward extremity of said combustion-box and serve to effect a tight joint with the boiler-shell extension.

In boilers of this class, in order to produce perfect operation and the desired combustion of the gases, a rear combustion-box is a necessity. As heretofore constructed, this combustion-box has generally been formed separable from the boiler-shell extension and has had one extremity secured to the rear flue-sheet for supporting said flue-sheet and the other extremity secured to the extremity of the boiler-shell extension. Experience has demonstrated that the products of combustion

rush through the fire-flue F into the combustion-box H, which they heat to a great temperature, and in the aforesaid construction of boiler I have found that an inadequate amount of water surrounds the combustion-box, especially when the water is low, and that thereby the great heat developed cracks or quickly burns out the combustion-box, and its replacement can only be effected at a great cost for time and labor. Moreover, in this construction the combustion-box is necessarily of smaller diameter than the boiler-shell extension, and the great heat developed causes the joints of said combustion-box to leak.

By my improved construction I form the

combustion-box of greater diameter than the boiler-shell extension, thereby increasing the area of the combustion-box, and I removably secure said shell to the boiler-shell extension, 5 and thus enable the ready replacement of a worn combustion-box at a minimum expense for material.

It will be particularly noted that my improved combustion-box has no water-joints 10 whatever, and thereby all leakage is absolutely prevented. Moreover, the said combustion-box may be composed of cast-iron instead of wrought-iron, which must necessarily be the material for combustion-boxes supported within the boiler-shell extension, and thereby the cost of my improved boiler is greatly decreased.

In order to prevent the direct contact of the products of combustion with the inner 20 surface of the removable combustion-box H, I provide any suitable construction of baffle-plate I. As illustrated, this baffle-plate is composed of the angularly-bent top portion i and the rounding extremities i', and is supported by eyebolts i², whereby when burned out, its replacement is enabled without necessitating the use of skilled labor.

My invention is of particular advantage 30 when used in traction-engines, since it frequently occurs that the combustion-box is burned out or injured when far removed from skilled labor and boiler-shops, and in this case by providing himself with additional combustion-boxes the user or owner of the boiler can quickly and with unskilled labor remove the old combustion-box and replace it with a new one, and without necessitating the stoppage of operations but for a short time.

The operation of my invention will be 40 readily perceived from the foregoing, and it will be understood that I do not limit my invention to the precise detail construction of

its parts, since the same may be somewhat varied without departing from the spirit thereof.

Having thus fully described my invention, what I claim as new, and desire to secure by Letters Patent, is—

1. In a boiler, the combination of a boiler-shell having an extension, an annular bearing 5c provided on the outside of said extension, a combustion-box encircling said bearing, and screws for removably securing said box to said bearing, substantially as and for the purpose described.

2. In a boiler, the combination of a boiler-shell having an extension, a rear flue-sheet, rivets for securing said flue-sheet to said extension, an annular ring secured to the outside of said extension in front of said securing-rivets, said ring being formed of greater thickness than the adjacent heads of said rivets, and a combustion-box removably secured to said ring, substantially as and for the purpose specified.

3. In a boiler, the combination of a boiler-shell having an extension, an annular bearing provided on the outside of said extension, a combustion-box encircling said bearing, movable clamps for removably securing said box 70 to said bearing, a fire-flue F, discharging within said combustion-box, and return-flues leading from said combustion-box, substantially as and for the purpose specified.

In testimony whereof I have hereunto 75 signed my name, in the presence of two attesting witnesses, at Buffalo, in the county of Erie, in the State of New York, this 29th day April, 1890.

CARLETON SPRAGUE.
